SEWING MACHINE

Frank A. Kucera, Chicago, Ill., assignor to Union
Special Machine Company, Chicago, Ill., a cor-
poration of Illinois

Application January 29, 1938, Serial No. 187,590

15 Claims. (Cl. 112—2)

This invention relates to sewing machines. More particularly it has reference to sewing machines useful in attaching button stay tape or the like to the body fabrics of garments with a portion of the tape projecting outward beyond the edge of the body fabric. Due to uneven feeding of the tape and the body fabric in operations of the kind referred to, difficulty is ordinarily experienced in preventing the formation of crooked and distorted seams. This is especially true in applying non-elastic tapes to the edges of knitted or similar materials which, as a consequence of their elasticity or looseness of texture, have a tendency to stretch during feeding.

The chief aim of my invention is to overcome the above drawbacks which desideratum I attain, as hereinafter more fully disclosed, through provision, in addition to a main feeding element and an opposing presser foot arranged to engage the work at the overlap, of an auxiliary feeding means including a feeding element in the form of a wheel disposed laterally adjacent the needle with its axis substantially in the plane of the latter, and an opposing resilient non-rotative element for engaging the free projecting portion of the tape, or binding and causing it to be pressed against the periphery of the wheel. Also as subsequently disclosed herein, I provide a differential feeding element for engaging the body fabric alone inward of the overlap and in advance of the main feeding element, and an independently-yielding presser foot portion to oppose said differential feeding element.

In connection with feeding mechanism having the foregoing attributes, it is a further aim of my invention to provide means convenient for ready manipulation by the operator of the sewing machine, whereby the feeding movement of the differential feeding element can be adjusted while the machine is running to insure uniform feeding of the body fabric in respect to the tape.

Another object of my invention is to preclude impartation of excessive movements to the auxiliary feeding wheel during high speed operation of the sewing machine. This objective I realize in practice through interposition between said wheel and a rotary clutch actuator therefor, of means whereby shifts of the actuator so small as to be uninfluenced by momentum, are magnified incident to transmission to the wheel so that the feeding effect of the latter is not only positive but accurate in progressing the tape concurrently with the body fabric.

Other objects and attendant advantages will appear from the following detailed description of

the attached drawings, wherein Fig. I is a view, partly in front elevation and partly in longitudinal section, of a sewing machine embodying the present improvements.

5 Fig. II is a fragmentary view in plan section taken as indicated by the arrows II—II in Fig. I.

Fig. III is a fragmentary plan section at a lower plane taken as indicated by the arrows III—III in Fig. I.

10 Fig. IV is a fragmentary detail view in plan showing a portion of the work support of the machine, the throat plate and certain of the feeding elements.

Fig. V is a transverse sectional view taken as 15 indicated by the arrows V—V in Figs. I and III with portions of the machine frame broken away, and showing more particularly the means whereby the feeding action of the differential feeding element is controlled.

20 Fig. VI is a similar view in a different transverse plane taken as indicated by the arrows VI—VI in Figs. I, II and III.

Fig. VII is likewise a transverse sectional view taken as indicated by the arrows VII—VII in Figs. 25 I and II, showing more particularly the actuating means for the auxiliary feeding wheel.

Fig. VIII is a fragmentary detail sectional view on a larger scale taken as indicated by the arrows VIII—VIII in Figs. II and IX, and showing 30 how the several feeding elements cooperate in progressing the work on the work support; and

Fig. IX is a fragmentary detail view in transverse section taken as indicated by the arrows IX—IX in Figs. II and VIII.

35 The machine chosen for convenience of illustrating my invention is of the flat bed type having a base 1 surmounted by a horizontal work support 2 which is overreached by a longitudinally extending arm 3 with a head 4 at its free 40 end wherein is guided a vertical bar 5 carrying a needle 6. By suitable means (not illustrated) within the arm 3, the needle bar 5 is reciprocated and the needle 6 thereby moved up and down through a hole 7 in a throat plate 8, see Figs. IV and VIII, which is set into an opening in the work support 2. Arranged to cooperate with the needle

45 6 below the work support 2 is a looper 9 which is fulcrumed to swing about a stud 10 engaging laterally into a rocker sleeve 11, said sleeve being 50 mounted for oscillation about a shaft 12 journaled in upstanding bearing lugs 13 on the base 1 of the machine. Secured to the rock shaft 12 is an arm 14 which, through a strap link 15 is connected to an eccentric 16 on the main drive shaft 17 of the machine. After common practice, the

drive shaft 17 is journaled in bearing lugs 18 (Fig. III) on the base 1 and provided at its outer end with a combined hand and belt wheel 19 so that the machine may be operated either manually or by power. By the means just described, needle avoiding movements are imparted to the looper 9 in a well known manner. Projecting from one side of the looper 9 is a ball stud 20 which, through an adjustable link 21, is connected to a similar ball stud 22 on an arm 23 extending upwardly from a rock shaft 24 journaled in the base 1 of the machine. Through rocking movements transmitted to the shaft 24 by suitable means such as disclosed for example in U. S. Patent No. 2,128,120, granted to N. V. Christensen et al. on August 23, 1938 and actuated from the main drive shaft 17, loop engaging movements are imparted to the looper 9. As shown in Fig. I, sewing threads T and T' are directed by way of suitable guides and tensions from individual sources of supply (not illustrated) to the needle 6 and the looper 9, respectively.

Like the needle bar 5, the presser bar 25 of the machine is confined to up and down movement in the head 4, its upward movement being resisted by a leaf spring 26 extending longitudinally over the arm 3. The spring 26 has its rear end suitably anchored beneath the cap or cover 27 for the column or standard 28 of the machine frame, and its front end is clevised to engage over the horizontal flange 29 of a stirrup 30 at the top end of the presser bar 25. The finger nut shown at 31 serves as a means for regulating the pressure of the spring 26. Affixed by screws 32 to the bottom end of the presser bar 25 is a presser foot 33 which will be referred to again later.

Arranged longitudinally of the front of the machine is a folder 35 for stay tape which is generally like the folder disclosed in U. S. Patent No. 1,884,248, granted to A. S. Riviere on October 25, 1932, in that it merges from flat upright tubular cross section at its receiving end to horizontal U-shaped cross section at its delivery end and in that it is formed with a laterally directed mouth at its delivery end through which the tape emerges longitudinally folded with narrow edge margins thereof retroverted inwardly as at M, M in Fig. IX. The folder is, however, in this instance, mounted on an arm 36 having a fulcrum connection with the machine base 1 at 37 (see Fig. II) so as to be retractable for convenience of threading the tape and when access must be had to the mechanism beneath the work support. From Figs. II and VIII, it will be further noted that the folder 35 delivers the tape S with the retroverted margins M of its folds centered in respect to the needle 6 and lapping corresponding narrow edge margins at opposite sides of a body fabric F which is concurrently delivered to the machine; with the doubled portion of the tape projecting outwardly beyond the overlap. Before entering the folder 35, the tape S passes through forked guides 38 which impose a definite amount of drag to keep it taut.

Except as hereinafter definitely pointed out, the feeding mechanism of the machine resembles that of U. S. Patent No. 1,884,489, granted to F. F. Zeier on October 25, 1932. Briefly described, this feeding mechanism comprises a main feed dog 39 and a differential feed dog 40. As shown in Figs. III and VI, the main feed dog is mounted, with capacity for lateral adjustment on the end of an arm 41 which overreaches the main shaft 17 and which is pivotally connected at 42

to a rocker 43 secured to a shaft 45 whereof the ends are journaled in spaced bearings 46 upstanding from the base 1 of the machine adjacent the rear edge. The differential feed dog 40, 5 on the other hand, is secured with capacity for vertical adjustment to a head 47 at the front end of a horizontal slide rod 48 having guidance for axial reciprocation in spaced lugs 49 projecting outward from one side of the arm 41. Affixed to the rod 48 in the interval between the guide lugs 49 is a collar 50 with a lateral projection 51 (Figs. III and IX) which extends outwardly through a longitudinal slot 52 in the arm 41 and which engages between a pair of guide plates 53 secured to the opposite side of said arm, so that the rod 48 is held against rotation during its reciprocations. Up and down or lift movements are imparted to the main and differential feed dogs 39 and 40 by virtue of connection of an underreaching extremity 55 of the arm 41, through a pendant link 56 to an eccentric 57 on the main shaft 17. The main and differential feed dogs 39 and 40 derive their horizontal to and fro or feeding movements in turn from a crank 58 at the front end of the main shaft 17, see Fig. V. As shown the crank 58 is coupled, by means of a drop link 59, with the end of a forwardly-extending horizontal arm 60 which is clamped to a laterally projecting stud 61 on the rocker 43. Pivotally connected at one end to a stud 62 on the collar 50 is a link 63 whereof the other end is bifurcated to straddle a plate 65 secured by screws 66 to the rocker 43. As shown in Fig. VI, the plate 65 has an arcuate slot 65a whereof the curvature is substantially concentric with the pivot center 62 of the link 63 when the feed dogs 39, 40 are in elevated or active position, said slot being engaged by a screw bolt 67 which extends through it and through the extremities of the bifurcated end of the link 63, see Fig. III. By moving the bolt 67 up and down in the arcuate slot 65a of the plate 65, it will be evident that the feed movement imparted to the differential feed dog 40 may be either increased or decreased with respect to that of the main feed dog 39.

In order to adapt a sewing machine of the character described up to this point to the purposes of my invention, I have made provisions as follows:

As shown in Figs. IV and VIII, the main feed dog 39 is formed with a relatively long row of teeth 39a which project upwardly through a slot 68 in the throat plate 8 at the left of the needle hole 7 so as to upwardly engage the body fabric F, inward of the overlap between the said fabric and the tape S. The main feed dog 39 is moreover formed with a short row of teeth 39b which project upwardly through another opening 69 in the throat plate 8 rearward of the needle hole 7 with respect to the direction of feeding and which is adapted to engage the work from beneath at the overlap between the body fabric F and the tape S. The portion 39b of the main presser foot 39, it will be noted from Figs. III and VIII is opposed from above by the presser foot 33 whereof the width corresponds substantially to that of the overlap between the fabric F and the tape S. The differential dog 40 has but a single row of teeth 40a which project upwardly through the opening 68 of the throat plate 8 ahead of the portion 39a of the main feed dog 39 with regard to the direction of feeding so as to engage only the body fabric from beneath inward of the overlap between the latter and the tape

S. The differential feed dog 40 is opposed in its action by an auxiliary presser foot portion 70 which engages the fabric F from above and which lies directly adjacent the main presser foot 33 to the left of the needle 6 as shown in Fig. II. The auxiliary presser foot 70 is pivotally connected at 71 to one side of the shank 33a of the main presser foot 33 and is subject to the downward pressure of a relatively light spring 72, see Fig. VI.

The means which I have devised for varying the feed stroke of the differential feed dog 40 includes a shaft 73 which is journaled in another bearing 75 on the base 1 of the machine as shown in Figs. III and VI. Affixed to the inner end of the shaft 73 is an arm 76 whereto is pivotally connected at 77 a shifting member 78 whereof the upper end is bifurcated to slidably engage the shank of the bolt 67. A pendant tail 78a of the shifting member 78 is pivotally connected at 79 to a parallel arm 80 on a rock shaft 81 journaled in the bearing 75 directly below the shaft 73. To the outer end of the shaft 73 is secured a lug 82 having a horizontal projection 82a engaged by one end of a torsion spring 83 which is coiled about the shaft 73 and which has its other end anchored to a stud 85 on the bearing 75. The spring 83 induces counter-clockwise rotation in the shaft 73 and thereby tends to urge the bolt 67 downwardly of the arcuate slot 65a in the plate 65 on the rocker 43. The lug 82 just referred to also has a pendant projection 82b tapped to receive the shank of a clamp screw 86 which passes through an arcuate slot 81a in a finger 87 at the outer end of the shaft 73 and which serves as a means for adjustably securing said lug to said finger. Under the action of the spring 83, the finger 87 is yieldingly maintained in contact with the inner end of an adjusting stem 88 which threadedly engages a bracket 89 secured by screws 90, to the base 1 and which extends outwardly from beneath the work support 2 to a point beyond the pendant flange 2a of said work support at the front of the machine where it is fitted with a manipulating knob 91. A leaf spring finger 92 secured to the bracket 89 cooperates with a circumferentially grooved collar 93 on the stem 88 to prevent accidental displacement of the latter in adjusted positions.

The auxiliary feeding means which I have provided for assisting the feeding means just described in progressing the work on the work support 2 includes a circumferentially-toothed wheel 95, which, as shown in Figs. II and VIII is positioned immediately inward of and to the right of the main presser foot 33 so as to engage the free extended portion of the tape S from above, the axis of said wheel being substantially in the plane of the needle 6, that is to say, just slightly in advance of the needle in the direction of feeding. As shown in Figs. II and IX, the wheel 95 is affixed to a short shaft 96 journaled in a bearing member 96a which is secured by headed screws 96b to a horizontal arm 97 pivotally connected at 98 to the shank 33a of the main presser foot 33 at the side opposite that occupied by the supplemental presser foot 70. The shanks of the screws 96b, it will be noted, pass through slots 97a in the arm 97 so that the wheel 95 can be positionally adjusted in the line of feeding. The arm 97 has a tail portion 99 with a longitudinal groove 100 in one of its lateral edges engaged by a circumferential flange 101a on an adjusting screw 101 which is threaded into the head of a stud 102 free to rotate in a rearward projec-

tion 103 on the presser foot shank 33a. By virtue of this arrangement, the arm 97 may be shifted about the pivot 98 to adjust the wheel 95 up and down relative to the bottom of the main presser foot 33. As shown in Figs. VIII and IX, the wheel 95 is opposed by a non-rotative element in the form of a flexible tongue 105 of sheet metal, which, see Fig. IV, engages the extended portion of the tape S from beneath, said tongue lying adjacent the portion 39b of the feed dog 39 and being secured at one end to the throat plate 8 by screws 106 so that it may move up and down within a clearance recess 107 in said throat plate. Upward movement of the tongue 105 is limited by coaction of its downwardly curved and retroverted end projections 105a with the underside of the contiguous edge 108 of the throat plate. The wheel 95 is intermittently rotated in timed relation with the movements of the feed dogs 39, 40 by mechanism comprising a roller clutch 109 which is mounted on a horizontal shaft 110 whereof the ends are journaled in a bearing bracket 111 affixed to the top of the work support 2. The clutch 109 (Figs. II and VII) may be of any well known construction, and, as shown, is operated from an eccentric 112 on the main shaft 17 through a horizontal link rod 113, the outer end of the link rod engaging a ball stud 115 which is adjustable along a longitudinal slot 116a in the actuating arm 116 of said clutch. Affixed to the clutch shaft 110 at the front end is a spur gear 117 which meshes with a spur pinion 118 on a short shaft 119 journaled on a supplemental bracket 120 attached to the bearing bracket 111. A pair of universal joint connections, 121, 122, serve to couple the short shaft 119 of the pinion 118 directly with the shaft 96 of the feeding wheel 95, so that said wheel may rise and fall with the presser foot 33 without attendant interruption in its intermittent rotative movements during feeding. A protecting shield of sheet metal is placed over the feed wheel driving mechanism, said shield being made in two sections 123, 124, which are separately secured, by screws 125, 126, to the machine frame.

From the foregoing, it will be apparent that in view of my improved construction, the work will be uniformly and positively progressed in the sewing machine, since, in being fed, it is engaged not only in the region of the overlap between the body fabric and the stay tape by the portion 39b of the main feed dog 39, but at opposite sides of the overlap respectively by the portion 39a of said main feed dog, and the wheel 95, excess movement or overthrow of the latter during high speed operation of the machine being precluded through interposition between it and its actuator of the gearing 117, 118. At the same time, the stretch of the body fabric is taken up by the cooperative action of the differential feed dog 40, which, through manipulation of the regulating stem 88 can be controlled while the machine is in operation, with consequent avoidance of any distortion or irregularity in the finished seam. Again, the chances of skewing or twisting of the work during the retractive strokes of the feed dogs 39 and 40 are nullified by reason of the fact that it is held down at one side of the needle 6 at the point of stitch formation (the wheel being substantially in the lateral plane of the needle as hereinbefore pointed out) and by the supplemental presser foot at the opposite side, while the main presser foot 33 bears down upon it directly in the line of seaming both forwardly and rearwardly of the needle.

Having thus described my invention, I claim:

1. In a sewing machine for attaching relatively inelastic tape in partially overlapping relation along an edge of relatively elastic body fabric, a reciprocating needle; and intermittent feeding means for concurrently progressing the tape and the body fabric for penetration by the needle within the width of the overlap, said feeding means including a main feed dog which engages both the tape and the body fabric rearward of the needle with regard to the direction of feeding, a differential feed dog which engages the body fabric alone inward of the overlap and in advance of the needle, means for operating the differential dog at a different rate than the main feed dog, an auxiliary feeding device which engages the projecting portion of the tape alone rearward of the needle, a main presser foot to coact with the main feed dog, an independently movable presser foot to coact with the differential feed dog, and an independently movable yielding element to coact with the auxiliary feeding device.

2. In a sewing machine for attaching relatively inelastic tape in partially overlapping relation along an edge of relatively elastic body fabric, a reciprocating needle; and intermittent feeding means for concurrently progressing the tape and the body fabric for penetration by the needle within the width of the overlap, said feeding means including a main feed dog which engages both the tape and the body fabric from beneath rearward of the needle with regard to the direction of feeding, a differential feed dog which engages the body fabric alone from beneath inward of the overlap and in advance of the needle, means for operating the differential dog at a different rate than the main feed dog, rotary feed wheel means which engages the projecting portion of the tape alone from above rearward of the needle, and individually-associated independently-yielding members operable to cause the work to be engaged by said feed dogs and wheel.

3. In a sewing machine for attaching relatively inelastic tape in partially overlapping relation along an edge of relatively elastic body fabric, a reciprocating needle; and intermittent feeding means for concurrently progressing the tape and the body fabric for penetration by the needle within the width of the overlap, said feeding means including a main feed dog which engages both the tape and the body fabric rearward of the needle with regard to the direction of feeding, a differential feed dog which engages the body fabric alone inward of the overlap and in advance of the needle, means for operating the differential dog at a different rate than the main feed dog, independently movable main and auxiliary presser feet to coact respectively with the main and differential feed dogs, a feed wheel carried by the main presser foot for engaging and progressing the projecting portion of the tape alone rearward of the needle, and a yielding element to coact with said wheel.

4. In a sewing machine for attaching relatively inelastic tape in partially overlapping relation along an edge of relatively elastic body fabric, a reciprocating needle; and intermittent feeding means for concurrently progressing the tape and the body fabric for penetration by the needle within the width of the overlap, said feeding means including a main feed dog which engages both the tape and the body fabric rearward of the needle with regard to the direction of feed-

ing, a differential feed dog which engages the body fabric alone inward of the overlap and in advance of the needle, means for operating the differential dog at a different rate than the main feed dog, and a feed wheel which engages the projecting portion of the tape alone rearward of the needle, an intermittently rotated shaft, and interposed means whereby the intermittent movements of said shaft are magnified incident to transmission to the feed wheel.

5. In a sewing machine for attaching relatively inelastic tape in partially overlapping relation along an edge of relatively elastic body fabric, a reciprocating needle; and intermittent feeding means for concurrently progressing the tape and the body fabric for penetration by the needle within the width of the overlap, said feeding means including a main feed dog which engages both the tape and the body fabric rearward of the needle with regard to the direction of feeding, a differential feed dog which engages the body fabric alone inward of the overlap and in advance of the needle, means for operating the differential dog at a different rate than the main feed dog, a feed wheel means which engages the projecting portion of the tape alone rearward of the needle, an intermittently rotated shaft, and a train of intermeshing gears whereby the intermittent movements of the shaft are magnified incident to transmission to the feed wheel.

6. In a sewing machine for attaching relatively inelastic tape in partially overlapping relation along an edge of relatively elastic body fabric, a reciprocating needle; and intermittent feeding means for concurrently progressing the tape and the body fabric for penetration by the needle within the width of the overlap, said feeding means including a main feed element which engages both the tape and the body fabric rearward of the needle with regard to the direction of feeding, a differential feed element which engages the fabric alone inward of the overlap and in advance of the needle, means for operating the differential feed element at a different rate than the first mentioned feed element, an auxiliary feeding device which engages only the projecting portion of the tape, a main presser element to cooperate with the main feed element, an independently movable presser element to coact with the differential feed element, and an independently movable yielding element to coact with the auxiliary feeding device.

7. A sewing machine according to claim 6, including a guide for guiding the body fabric, and a folder for folding the tape about its longitudinal median and determining placement of the tape symmetrically around the edge of the body fabric with its folds partly overlapping said edge.

8. A sewing machine according to claim 2, further including a support for the feed wheel, and means whereby the support is secured to the main presser foot with provision for vertical adjustment of the wheel relative to the presser foot as well as adjustment thereof in the direction of feeding.

9. In a sewing machine stitch forming means; and intermittent feeding means for progressing the work relative to the stitch forming means, including separately actuated feeding elements in excess of two arranged side by side, one of said elements being in the form of a feed wheel, and the others in the form of feed dogs, a yielding member for causing the work to engage the feed wheel, and a pair of separate yielding members

for causing the work to be engaged by the respective feed dogs.

10. A sewing machine according to claim 9, including means for individually adjusting the feeding movements of the several feeding elements.

11. A sewing machine according to claim 9, wherein certain of the feeding elements engage the work from above and others engage the work from beneath.

12. A sewing machine according to claim 9, wherein the stitch forming means includes a needle; and wherein certain of the feeding elements engage the work in advance of the needle with regard to the direction of the feeding, and others engage the work rearward of the needle.

13. In a sewing machine stitch forming means including a needle; and feeding means for progressing the work relative to the needle including three separately actuated feeding elements, one in the same plane with the needle in the direction of feeding, and the others respectively at opposite sides of the needle, two of said elements having the form of feed dogs and the third having the form of a feed wheel, a pair of 25 independently yielding members for causing the

work to be engaged by the respective feed dogs, and a separate yielding member for causing the work to engage the feed wheel.

14. A sewing machine according to claim 13, 5 wherein the center feeding element and one of the other acts upon the work from beneath, and the third one acts upon the work from above.

15. In a sewing machine, stitch forming means including a needle; and feeding means for progressing the work relative to the needle including three separately actuated feeding elements, one in the same plane with the needle in the direction of feeding, and the others respectively at opposite sides of the needle, the center feeding element and one of the side elements being in the form of four-motion feed dogs which operate on the work from beneath, and the third element being in the form of an intermittently rotated wheel which operates on the work from above, a pair of independently yielding members for causing the work to be engaged by the respective feed dogs, and a separate yielding member for causing the work to engage the feed wheel.

FRANK A. KUCERA.
